UNITED STATES PATENT OFFICE.

JOSEPH C. FIELD, OF ORANGE, NEW JERSEY, ASSIGNOR TO WESTERN ELECTRIC COMPANY, INCORPORATED, OF NEW YORK, N. Y., A CORPORATION OF NEW YORK.

SIGNALING SYSTEM.

1,369,019.

Specification of Letters Patent. Patented Feb. 22, 1921.

Application filed November 26, 1917. Serial No. 203,950.

To all whom it may concern:

Be it known that I, JOSEPH C. FIELD, a citizen of the United States, residing at Orange, in the county of Essex and State of 5 New Jersey, have invented certain new and useful Improvements in Signaling Systems, of which the following is a full, clear, concise, and exact description.

This invention relates to signaling systems, and more particularly to selectively operated signaling systems in which a plurality of waystations connected with a single line circuit are each provided with a selectively operated signal controlling device.

15 The object of this invention in general is to provide an improved organization of apparatus and circuits whereby any party on a circuit may, without assistance, call and communicate with any other party on the 20 same circuit without operating the signals at any of the other waystations on the line.

In accordance with the general features of this invention the selectively operated devices are each simplex to ground from the 25 middle point of an inductive bridge, and a key is provided at each waystation for charging and discharging the inductive devices of each bridge through the selectively operated device associated therewith and 30 from a common source of energy which is connected in simplex of the line through a high impedance retardation coil.

The drawing is a diagram of circuits and apparatus illustrating this invention.

35 In the drawing 5 and 6 designate a pair of line wires with which are associated waystations A and B. At each of the waystations A and B is a selectively operated signal controlling device, which comprises 40 in general a polarized operating magnet 7, a step-by-step element 8 carrying a contact arm 9 and a stationary contact element 10. A centrally pivoted armature 11 is adapted, in response to alternating current impulses 45 through the magnet 7, to operate a stepping pawl 12 to advance the step-by-step element 8 into a position where the contact arm 9 will engage the stationary contact 10, in which position it is held by means of a 50 spoon-ended spring 13 engaging with a pin

14 in the step-by-step element 8 upon the cessation of the last impulse of the combination of selecting impulses. When the spoon-ended spring 13 of a selector engages its associated pin 14, the contact arm 9 is 55 in engagement with the stationary contact 10, thereby closing a local circuit through the bell 15 which thereupon operates to furnish a signal to the attendant at the station. During the operation of the bell 15 60 the resistance 40 is intermittently bridged across the line wires 5 and 6 in series with one winding of the bell magnet and the condenser 41 to transmit an answer back signal to the calling station to indicate to the operator thereat (whose receiver 50 is also bridged across the line wires) that the bell at the called station is operated. The condenser 41 is for the purpose of preventing the establishment of a direct current bridge 70 across the line wires, which might interfere with the proper operation of the selector. The selectively operated signal controlling device, illustrated in the drawing, is a code selector of the type disclosed in my copending application, Serial No. 98,384, filed May 18, 1916, Patent No. 1,343,256 issued June 15, 1920. A detailed description of the construction and operation of this selector will be found in this copending application, 75 from which it will be seen that since the selector functions in response to a code or combination of impulses, the station contacts 9 and 10 of one station only, namely the called station, are closed in response to a given 80 combination of impulses whereby only the bell at the desired station operates. After the operation of the bell at the called station, another impulse may be sent over the line to cause the element 8 to advance one 85 step, moving the pin 14 out of engagement with the spring 13, whereupon upon the cessation of the impulse the element 8 returns to normal position under the action of a coiled spring 42, one end of which is secured to the shaft upon which the element 90 8 is mounted and the other end of which is held in fixed position.

Connected to the line wires 5 and 6 at each of the waystations is an inductive 100

bridge comprising two impedance coils 20 and 21, and two condensers 22 and 23, the impedance coils and condensers of each bridge being included in serial relation with 5 respect to each other. One side of each of the magnets 7 is connected with ground, the other being connected with the inductive bridge at a point between the condensers 22 and 23. A battery 25 located at one end 10 of the line wires 5 and 6 is connected in simplex of the line wires through high-impedance, low-resistance retardation coils 27, 27 and the windings 28, 28 of a simplex coil.

Located at each of the waystations is a 15 key lever 30 connected between the condenser 23 and line wire 6, and co-operating with two contacts 31 and 32. Contact 31 connected with ground is adapted to be opened and closed intermittently during the 20 operation of the key in calling, while contact 32 connected between condenser 22 and line wire 5 is adapted to be continuously closed during the operation of the key lever 30.

The operation in this system is as follows: 25 Normally the condensers 22 and 23 are charged to the potential of the battery 25. When the calling key at any station is operated, the contact 32 will be closed and remain closed during the complete operation 30 of the key. The contact 31 is caused to make and break contact to give the correct combination of impulses to operate the selector at the station called. Each time that the contact 31 is closed, the condensers 22 and 23 35 at each of the waystations are discharged through their associated selector windings, and when the key contact 31 is open, the condensers 22 and 23 charge through the windings of their associated selectors, thus 40 causing a flow of current impulses through the windings of the magnets 7 alternately in opposite direction to advance the associated step-by-step elements 8 until the station contacts of a desired station are closed.

45 The retardation coils 20 and 21 are of sufficient impedance to talking currents so that there will be no appreciable transmission loss due to this bridge at each station.

The line wires being in multiple in the 50 operation of the selectors, a much longer line with a greater number of stations can be operated with a given battery than would be possible in an ordinary bridged system.

What is claimed is:

55 1. In a signaling system, a metallic line circuit, a plurality of waystations associated therewith, a selectively operated polarized signal controlling device at each waystation connected between the opposite sides of the metallic circuit and ground, a signaling device at each waystation, a source of direct current supply having one pole grounded and its opposite pole connected to the two sides of the line circuit, circuit-interrupting

means at each waystation, and means at 65 each waystation responsive to the operation of the circuit-interrupting means at any waystation for causing a flow of alternating current impulses through the signal controlling device thereat for thereby rendering 70 the signal controlling devices selectively responsive for operating one of the signaling devices.

2. In a signaling system, a metallic line circuit, a plurality of waystations associated 75 therewith, a polarized signaling device at each of said waystations connected between opposite sides of said metallic circuit and ground, a source of direct current supply having one pole grounded and its opposite 80 pole connected to the two sides of the line circuit, circuit-interrupting means at each of said waystations, and means at each of said waystations responsive to the operation of the circuit-interrupting means at any 85 waystation for causing a flow of alternating current impulses through the polarized signaling devices.

3. In a signaling system, a metallic line circuit, a plurality of waystations associated 90 therewith, an inductive bridge connected with the metallic circuit at each of said waystations, a polarized signaling device at each of said waystations connected between the middle point of said inductive 95 bridge and ground, a source of current connected between the two sides of the line circuit and ground, and a circuit-interrupting device at each of said waystations, each adapted in its operation to charge and 100 discharge the inductive devices at all of the waystations through their associated polarized signaling devices to actuate them.

4. In a signaling system, a metallic line circuit, a plurality of waystations associated 105 therewith, a pair of condensers connected in bridge of the line circuit at each of said waystations, a polarized signaling device at each of said waystations connected to a point between said condensers and ground, a 110 source of current having one pole connected to opposite sides of said line circuit and its other pole connected with ground, and a circuit-interrupting device at each of said waystations, each adapted in its operation to 115 alternately charge the condensers at the several waystations through the associated signaling device in one direction and discharge the condensers therethrough in the opposite direction thereby to operate the signaling 120 devices.

5. In a signaling system, a metallic line circuit, a plurality of waystations associated therewith, a selectively operated polarized signaling device at each waystation connected 125 between opposite sides of the metallic circuit and ground, a source of direct current supply having one pole grounded and

its opposite pole connected to the two sides of the line circuit, circuit-interrupting means at each waystation, and means at each waystation responsive to the operation of the circuit controlling means at any waystation for causing a flow of alternating current impulses through the associated signal-

ing device thereby rendering the signaling device selectively responsive for signaling purposes. ¹⁰

In witness whereof I hereunto subscribe my name this 22nd day of November, A. D. 1917.

JOSEPH C. FIELD.
